United States Patent Office

Des. 194,398
Patented Jan. 15, 1963

194,398

DOLL OR SIMILAR ARTICLE

Hugh D. Riordan and Carl D. Johnson, both of 1260 Galena, Wichita, Kans.

Filed Aug. 6, 1962, Ser. No. 71,188

Term of patent 14 years

(Cl. D34—4)

FIG. 1 is a front elevational view of a doll or similar article showing our new design.

FIG. 2 is a rear elevational view of same.

FIG. 3 is a side elevational view showing one side of our doll or similar article.

FIG. 4 is an elevational view of the other side of our doll or similar article.

FIG. 5 is a bottom plan view of same.

FIG. 6 is a top plan view of the doll or similar article of our invention.

We claim:

The ornamental design for a doll or similar article, as shown.
